UNITED STATES PATENT OFFICE.

EDMUND B. WEDMORE, OF RUGBY, ENGLAND, ASSIGNOR TO GENERAL ELECTRIC COMPANY, A CORPORATION OF NEW YORK.

REVERSE-CURRENT DEVICE.

No. 848,944.

Specification of Letters Patent.

Patented April 2, 1907.

Application filed November 11, 1905. Serial No. 236,843.

To all whom it may concern:

Be it known that I, EDMUND B. WEDMORE, a subject of the King of Great Britain, residing at Rugby, England, have invented certain new and useful Improvements in Reverse-Current Devices, of which the following is a specification.

My invention relates particularly to electromagnetic devices used in connection with electric-circuit breakers for causing the operation of a circuit-breaker upon reversal of the current in a circuit or circuits controlled thereby.

In the form of this device now commonly used a current and a potential coil are arranged to act on a magnetic plunger, the two coils being opposed to one another when the direction of the current in the circuit upon which they are connected is normal and assisting each other upon reversal of current, so as to move the plunger and cause the opening of an automatic circuit-breaker. Such a device will be caused to operate by the flow of sufficient current in the normal direction, the magnetizing effect of the series coil being sufficient to overcome that of the shunt-coil and to provide in addition the necessary magnetic flux to operate the plunger. It is commonly desirable to obtain a relatively low setting of the device for operation on reverse current and high setting for operation on overloads in the normal direction. The ratio between the overload and reverse-current setting may be increased by so proportioning the potential-winding that only a small increase of magnetizing force is required to cause the device to operate. This adjustment is accompanied by two disadvantages. First, the device is liable to operate on a rise of potential occurring and independently of reversal of current; secondly, the reverse current required to cause the device to operate will be greatly increased should the potential be much reduced below normal value.

The main object of my invention is to provide improved means for increasing the ratio between the overload and reverse-current settings in which the disadvantages accompanying the above adjustment are materially reduced.

A further object of the invention is to obtain a proportional adjustment of the overload and reverse-current settings of a reverse-current device.

The invention is intended to be applicable more particularly for reverse-current devices used on alternating-current circuits, and is designed also for overcoming some of the disadvantages peculiar to devices of this kind. It will be obvious, however, that in some of its features the invention is applicable to devices for use on continuous-current circuits.

Referring to the accompanying drawings, in which like parts are designated by the same reference-letters, Figure 1 is a sectional elevation of a reverse-current device constructed according to one form of my invention, and Figs. 2 and 3 are similar views of modified forms of device.

I construct the reverse-current device in the usual form of a compound-wound iron-clad solenoid consisting of a cylindrical iron casing *a*, secured to a suitable support, as *a'*, and having a removable iron cover *b*, inclosing a pair of windings *c* and *d*. The winding *c* is adapted to carry the main current in a supply-circuit or a current proportional thereto, and the winding *d* is adapted to be connected across the terminals of the circuit or in the case of high-tension alternating-current electric circuits to be supplied from the secondary of a potential-transformer connected across the circuit. The solenoid is fitted round a central tube *e*, of brass or other suitable material, which is secured at its lower end into the bottom of the casing *a*. Part of the core *f* is attached to the cover *b* and projects along the axes of the two coils, its free extremity being separated by an air-gap *g* from a movable iron plunger *h*, located in a guide-tube *i* and supported on an adjustable screw-plug *j*. The setting of the device is regulated by adjustment of the length of the air-gap *g* by screwing up or down the plug *j*. A loosely-fitting plunger *k* passes axially through and projects at both ends from the fixed core *f* of the solenoid. One end of this plunger is fitted with a contact *l*, adapted to short-circuit a pair of fixed contacts *m*, connected in the tripping-circuit of an automatic circuit-breaker, or the devices may be arranged to actuate directly mechanical means for releasing the circuit-breaker. In such case the release of the circuit-breaker-detaining catch is effected by the pin *n*, which moves with the plunger *h* in a slot *o*, formed in the guide-tube *i*. The movement of the plunger *h* in Fig. 1 for causing the cir-

cuit-breaker to operate by engagement with the plunger *k* is cushioned by the spring *p*, attached to the lower end of the plunger *k*.

In devices of this kind it has been customary to arrange the series coil in close proximity to or around the air-gap, separating the fixed core from the movable plunger. According to my invention I dispose the windings of the potential-coil *d* around the air-gap *g* and place the current-coil around a portion of the core or in general of the magnetic circuit remote from the air-gap. In the figures the current-coil *c* is arranged around the fixed part of the core *f*. By this means we promote magnetic leakage of the flux due to the series-solenoid across those portions of the magnetic circuit between the series solenoid *c* and the air-gap *g*. On the occurrence of an overload the magnetic flux density in the portion of the magnetic circuit surrounded by the series solenoid is greatly increased due to the series coil having to provide sufficient magnetizing force to overcome the magnetizing force of the potential-winding as well as to actuate the plunger and to provide the leakage flux. I may utilize, according to the proportions of the magnetic circuit of the device, the increased resistance to the passage of the magnetic flux caused by saturating the portion of the magnetic circuit embraced by the series winding to promote leakage in a manner obvious to those skilled in the art, or I may employ an iron ring *q*, located between the two windings, so as to increase the leakage, as shown in Fig. 1, or as an alternative I may employ a short-circuited winding consisting of a metal ring *r*, surrounding the core *f*, as shown in Fig. 3, or the core *f*, which in a device for use with alternating currents is laminated, may be made solid, so that the eddy-currents will be produced in it, which will modify the distribution of the magnetic flux.

I may so proportion the parts that the end of the movable plunger *h* adjacent to the air-gap shall be flush with or sunk below the bottom of the iron casing *a*, surrounding the solenoid, as shown in Fig. 2, thus increasing the tendency for the magnetic flux to leak to parts of the casing and away from the movable plunger. In this case the flux from the current-coil *c* is distributed over the inside of the casing *a* and little of it reaches the plunger *h* on overloads. On reversal of current, however, the potential-coil *d* acts in the same direction as the coil *c* and directs the flux on to the plunger.

By means of my invention, as above described, I am enabled on installations where the maximum obtainable overload-current is not too great to put the overload setting outside the possible range of operation and at the same time to enable the device to operate on reversal of current accompanied by a large drop of potential without necessitating the

flow of so large a reverse-current as has been necessary in devices of the kind described above hitherto used. Furthermore, my invention, as illustrated more particularly in Fig. 1, may be used for the purpose of obtaining a proportional adjustment of the overload and reverse-current settings where it is desired that the device shall operate both on reversal of current and on overloads.

In the ordinary form of reverse-relay of the solenoid type in which the two windings are uniformly disposed about the gap instead of being separated, as in my invention, a small reduction of the gap will greatly alter the reverse current-setting and only slightly alter the overload setting. According to the devices already described so much leakage for the flux due to the current-winding on overloads is introduced as to put the overload setting very high and in some cases out of range, as already pointed out. An intermediate stage between the two extremes is obtainable, in which the overload adjustment is rapidly raised as the gap is reduced in length. By suitably proportioning the parts the overload adjustment may be caused to alter at the same rate approximately as the reverse-current adjustment. So long as one adjustment only is used it is necessary that the same should affect either only the reverse-current setting or only the overload setting or should affect them both in some useful and readily comprehensible manner. In the ordinary differential relay it is impossible to obtain any appreciable alteration of the overload setting, while the reverse setting is readily altered.

I have found it apparently impossible to obtain a very wide range of adjustment on the overload setting without altering the reverse-current setting; but a practically useful combination can be realized, as shown in Fig. 1, which affords a proportionate simultaneous adjustment of the two settings, the leakage being obtained by the iron ring *q*, forming a shunt to the flux of the coil *c*. Thus a relay operating on, say, one-fifth normal-load reverse-current and three times normal-load overload may be adjusted by moving the plunger so as to operate on overload of, say, six times normal load and on a reverse-current with the same setting of two-fifths normal load.

What I claim as new, and desire to secure by Letters Patent of the United States, is—

1. An electric protective device comprising current and potential coils, and an open magnetic circuit threading said coils and having an adjustable air-gap more remote from the current-coil than from the potential-coil.

2. An electric protective device comprising current and potential coils, an open magnetic circuit threading said coils and including a movable member, and means for promoting magnetic leakage of the flux of one

- of said coils away from said movable member.
3. An electric protective device comprising current and potential coils, an open magnetic circuit threading said coils including a movable member, and means for promoting magnetic leakage of the flux of the current-coil away from said movable member. 5
4. An electric protective device comprising current and potential coils, a magnetic circuit threading said coils, and a body of magnetic material between said coils for shunting the magnetic flux. 10
5. An electric protective device comprising current and potential coils, an open magnetic circuit threading said coils and having its air-gap disposed nearer to one coil than the other, and means for promoting magnetic leakage of the flux of the more remote 15 coil away from said air-gap.
6. An electric protective device comprising current and potential coils, an open magnetic circuit threading said coils and having its air-gap disposed more remote from the current-coil than from the potential-coil, and means for promoting magnetic leakage of the current-coil away from said gap. 20
7. An electric protective device comprising a casing of magnetic material, current 25 and potential coils contained therein, a fixed
- core attached to the top of the casing around which the current-coil is arranged, and a plunger movable within the potential-coil and normally situated with its upper extremity remote from the current-coil. 35
8. An electric protective device comprising a casing of magnetic material, current and potential coils therein, a fixed core attached to the top of the casing and extending downward within the current-coil, a plunger 40 movable within the potential-coil and normally situated with its upper extremity remote from the current-coil, and a short-circuited winding on the fixed core for shunting the flux of the current-coil. 45
9. An electric protective device comprising current and potential coils, a fixed core of high reluctance extending into one of said coils, and a coöperating plunger.
10. An electric protective device comprising current and potential coils, an open magnetic circuit threading said coils having the core embraced by the current-coil of high reluctance. 50

In witness whereof I have hereunto set my hand this 30th day of October, 1905.

E. B. WEDMORE.
